BENJAMIN A. MASON, OF NEW YORK, N. Y.

Letters Patent No. 65,100, dated May 28, 1867.

IMPROVEMENT IN MACHINES FOR MAKING SCREWS.

The Schedule referred to in these Letters Patent and making part of the same.

TO ALL WHOM IT MAY CONCERN:

Be it known that I, BENJAMIN A. MASON, of the city and State of New York, have invented and made a certain new and useful Improvement in Machinery for Shaving, Nicking, and Pointing Screw-Blanks; and I do hereby declare the following to be a full, clear, and exact description of the said invention, reference being made to the annexed drawing, making part of this specification, wherein—

Figure 1 is a side view of my machine.

Figure 2 is a vertical section of the same.

Figure 3 is a plan of the upper part of the machine.

Figure 4 is a sectional plan of the shaving and nicking mechanism between the lines *x* and *y*.

Figure 5 is a sectional plan below the line *y*.

Figure 6 is a similar view below the line *z*.

Figure 7 is an edge view, and

Figure 8, a side view, of the saw for nicking the heads.

Figure 9 is a detached elevation of the shaving mechanism; and

Figure 10 is an inverted plan of the shaving cutters.

Similar marks of reference denote the same parts.

The object of my invention is to shave or smooth the heads of screw-blanks, cut the nick or crease across the head, and dress off the point into a tapering form.

I arrange my machine so that three, four, or more blanks can be operated upon simultaneously and then moved forward to the next operation; and I construct my shaving, nicking, and pointing mechanism so that the several operations will be performed upon the blank while held in a definite and rigid position, but the operation of each device is discontinued before the blank is carried forward to the device for performing the succeeding operation.

In the drawing, *a* is the lower bed of the machine. *b* a bed supported upon the columns *c c* and *d d*, and upon the central portion of the bed *b* is a hub, *e*, extending up to the bed or arms *f*, from which rises the sleeve *g*, supporting the disk *h*, that in turn sustains the upper plate *k* by the columns *k'*. *l* is the central and actuating shaft, rotated by competent power, and giving motion through the pinion *i*, intermediate pinion *i'*, (fig. 1,) wheel *m*, shaft *m'*, and pinion *n*, to the cam-collar *n'* around the hub *e*. The bed *o* carries the blank-holders, hereafter described, and it is to be revolved progressively to present the blanks to the successive operations. To effect this, I provide pins, *1 1*, projecting upward from revolving cam-collar *n'*, (see fig. 6.) Each pin, *1*, acts successively upon a lever, *2*, set upon a fulcrum-stud on the bed *b*, the end of which lever *2* takes against a cam projection, *4*, on the under side of the bed *o*, (see dotted lines in fig. 5,) and partially revolves the same to carry the blanks from one operation to the next. This lever *2* is drawn back to its normal position (after the pin *1* clears the end thereof) by a spring, and the end of the lever is made as a hinged spring-latch, in order that it may spring downwards as it comes in contact with the bevelled side of the projection *4*, and after passing the same, spring up to be in position for the next operation. My machine may be constructed with any desired number of sets of shaving, nicking, and pointing devices. I have shown four such sets, and hence around the revolving bed *o* I have shown twelve blank-holders *o'*, in order that each blank-holder may be stopped the required number of times for allowing of the respective operations; that is to say, when the bed *o* is in one position, four rough-headed screw-blanks are fed into four of the holders *o'*, the bed *o* moves on, carrying said four blanks to the shaving mechanism for smoothing the head. Four more blanks are then received into the holders next following, and the first four blanks are carried to the mechanism that nicks the head at the same time that the point is being dressed off conically. The next motion of the bed *o* brings the blank-holders around to the point for the delivery of the first four blanks received, and for the reception and clamping of other blanks as soon as the bed commences to move again. By this arrangement the screw-blanks are presented successively to the mechanism effecting the different operations, and as the shaving, nicking, pointing, and feeding mechanisms are only duplicated in the four positions shown, the description will be made, generally, to set forth the construction and operation of one of each set of devices. The jaws *o'*, forming the blank-holder, are constructed and arranged so as to slide radially to the plate *o*, and each holder is closed after the blank is

dropped between its jaws; to effect which I employ a roller, 5, attached to the sliding jaw, and rolling against a flange on the ring ρ that is attached to the upper ends of the columns c c . This flange is curved, as shown at 7, so as to relieve the pressure on the rollers 5 and allow the jaw to be opened, which is done by a pin projecting downwards from the moving jaw that comes in contact with a stationary cam, 8, supported by the bed b , the upper surface of which cam 8 serves to arrest and sustain the screw-blank as it is delivered from the slide or raceway 6 between the jaws σ as the bed σ commences to move. 11 is a hole through which the pointed blank is allowed to drop when the jaws are opened as aforesaid. The end of the raceway 6 is made with spring fingers which grasp the blank below the head, and each blank in succession is forced down through these spring fingers at the right time by the feed-punch r that is caused to slide vertically by the lever 10 and cam 9 upon the wheel g , the latter being driven by the pinion 8, that receives motion from the pinion g' on the main shaft l . (See fig. 3.) A spring, r^3 , surrounding the feed-punch r , is employed to throw said feed-plunger r up as soon as the cam 9 has cleared the end of the lever 10. The device for shaving the heads of the screw-blanks consists of cutters 15, in a disk, t . (See fig. 10.) These cutters are of a shape adapted to the form of screw-head, so as to shave the top and edges or under side of the screw-head. The disk t is at the lower end of and revolved by the spindle s^3 , and said disk runs in a ring opening in the bed f . The spindle s^3 and disk t are rotated by the belt and pulleys s^1 and s^2 , or other convenient mechanism. The cutters 15 have to be open as they go down to place over the screw-head, then they have to be pressed towards each other to shave the head, then opened and raised, so as to let one screw-blank be carried away and another brought to place. This is effected by the cam-groove 18 around the gear q acting upon the slide-rod 17, that is guided in the disk h and upper plate k , and has a fork, t^2 , taking a groove around a cone or wedge, t^1 , that slides on the spindle s^3 . And 12 13 are arms on the fulcra 19, that at their upper ends set against the cam or wedge t^1 , and at their lower ends enter openings in the sliding cutters. 15 and 16 are springs that tend to keep the cutters apart. As the slide-rod 17 is lowered by the cam 18, the cutters 15, disk t , shaft s^3 , and cone t^1 all descend, the cutters being open, and the weight of the parts hanging by a collar or pin on the shaft s^3 above the cone t^1 . When the disk t reaches its seat in the ring on the bed f , the cutters do not descend further, but the cone t^1 being forced down, acts through the levers 12 to force the cutters 15 to the head of the blank and shave it by the revolution of the cutters and disk. The reverse motion first lifts the cone t^1 , allowing the cutters to be opened by the springs 16, and then lifts the parts bodily up from the head of the blank. The nicking mechanism consists of a saw, u , hung on a swinging frame, u' , depending from a bracket which is bolted upon the bed h . The saw is hung on an arbor that is rotated by a belt, v , from the pulleys s^1 passing over guide-sheaves to the sheave v^3 . The saw is oscillated to and fro across the head of the blank to nick the same, and this oscillating motion is derived from the slide-rod 17, bent lever 19, lever 20, and link 21, connecting the latter to the frame u' . The operation of nicking one head is done at the same time that the head of the succeeding blank is being shaved by the cutters 15, the cam 18 bringing both the shaving and nicking devices into operation. The blank is pointed by a hollow tool in the upper end of the rotary spindle v^1 . The spindle is rotated by a belt, v^2 , and pulley v^4 on the shaft l , and is slidden endwise at the same time, so as to come up to and operate upon the blank by means of the grooved collar 22, forked lever 23, and cam 24 on the lower part of the cam-collar v^1 . The spindle is forced down so soon as the cam 24 has passed the end of the lever 23 by a spring, 25. In order to hold the revolving plate or bed σ during each pause, I make use of the spring-bolt w , which enters successively different holes in said bed σ . The bolt is withdrawn at the proper time by a lever, w' , which is acted on by a cam on the wheel m .

What I claim, and desire to secure by Letters Patent, is—

1. The series of intermittently revolving jaws, in combination with the revolving shaft s^3 , cutter 15, and cone t^1 , constructed, arranged, and acting substantially as specified.
2. I claim the hanging saw u , actuated in the manner and by the means substantially as described, in combination with the blank-holders σ , for the purposes and as set forth.
3. I claim the pointing-tool secured upon the end of the revolving spindle v^1 , in combination with the lever 23, cam 24, and blank-holders σ , as and for the purposes set forth.
4. I claim the arrangement and combination of all the mechanism herein described, for shaving, nicking, and pointing screw-blanks, as set forth.

BENJ. A. MASON.
